UNITED STATES PATENT OFFICE.

ROWLAND S. NORTON, OF TROY, NEW YORK.

CREASING-MACHINE.

SPECIFICATION forming part of Letters Patent No. 240,534, dated April 26, 1881.

Application filed December 8, 1879.

To all whom it may concern:

Be it known that I, ROWLAND S. NORTON, of the city of Troy, county of Rensselaer, and State of New York, have invented a certain 5 new and useful Improvement in Creasing-Machines, of which the following is a full, clear, and exact description, reference being had to the accompanying drawings, which form a part of this specification.

10 The nature of my invention consists in providing a creasing-machine, to be run by steam or other power, with two parallel shafts, on the outer end of one of which is a creasing-wheel, working into a grooved wheel on the corresponding end of the other shaft, and a cloth-plate and a guide-bar and presser thereon to keep the article to be creased in position; and one object of my invention is to produce a suitable device for creasing collars and cuffs and 20 other articles, as a guide for turning down or in their edges uniformly for stitching.

In the drawings, Figure 1 is a plan or top view of my improved machine, and Fig. 2 a vertical section thereof on line $\alpha\alpha$ of Fig. 1.

25 Like letters of reference indicate corresponding parts in both figures.

It is well known to the manufacturers of collars and cuffs that collars and cuffs and some other articles are, necessarily, first run or 30 stitched together wrong side out, and are then turned out and stitched on the edges on the right side, and that after having been run or stitched on the wrong-side they must be turned right-side out and the edges turned down for 35 stitching; and it is also well known to such manufacturers, and is the fact, that in turning down such edges the uniformity or evenness of the fold depends entirely on the eyes of the workman, and it is rarely that a workman 40 can be found who can turn down such edges uniformly the entire length of such edges. Besides, such turning down is a slow as well as a difficult work, and involves comparatively considerable expense.

45 To obviate these with other difficulties is the object of my invention, and I proceed to describe it.

A is the bed-plate of the machine, adapted to be secured to a table or suitable platform 50 for operation.

Two uprights, B and C, a few inches apart,

are secured to or cast upon the bed-plate, and are of sufficient height to carry the shafts and their connections. The shafts D and E pass through and are supported by the uprights, 55 and work in suitable bearings. On the inner end of these shafts are cog-wheels, working into each other, and to one of these shafts the power is applied in the usual manner. The outer or opposite ends of these shafts project far enough 60 beyond the upright for the creasing device. Between the outer ends of these two shafts I secure to the upright B the cloth-plate H, of sufficient length and width for the goods which are to be creased.

65 On the outer end, preferably of the lower shaft, is the small wheel I, having a narrow groove around its periphery and projecting through a slot in the cloth-plate. At a corresponding point on the outer end of the other shaft is the small creasing-wheel J, having a rounded edge and fitting and working in the groove of the wheel I.

70 On the cloth-plate is an adjustable guide-bar, K, having slots through it corresponding with 75 holes through the cloth-plate, and having set-screws therein, by which the guide-bar can be adjusted on the cloth-plate at such distance from the creasing-wheel as the crease in the goods from the edge thereof is desired. Upon 80 this cloth-plate I also secure the adjustable spring-presser L, for holding the goods down upon the cloth-plate in front of the creasing-wheel. This presser may be a roller or a flat 85 piece of metal. However, I prefer a flat piece of metal, as it is less expensive and answers every purpose.

To the guide-bar K, I attach a small lever, M, one end being hooked under the presser L, by means of which the presser can be readily 90 raised for inserting thereunder the goods to be creased.

Under the outer bearing of the upper shaft 95 is a spiral spring, N, for lifting the edge of the creasing-wheel J out of the groove in wheel I when relieved from pressure, the bearing in the upper shaft in upright B moving loosely in grooves in the upright. To obtain the necessary pressure upon the creasing-wheel J, I attach one arm of the lever O to the top of the 100 upright B, so it will rest upon a pin in the center of the movable bearing of the upper shaft,

and to the outer end of this lever I suspend a weight sufficiently heavy to give the required pressure to the creasing-wheel.

Its operation is as follows: Power is applied 5 as hereinbefore set forth. The guide-bar is adjusted for the required distance between the edge of the goods and the creasing-point. The collar, cuff, or other article is then placed on the cloth-plate and under the presser and 10 creasing-wheel, when such collar or other article is rapidly drawn under the creasing-wheel and a deep and uniform crease made in the goods at the desired point, which serves as an unerring guide for the fold in the goods.

15 By the use of this machine much time and labor is saved in the folding of collars, cuffs, &c., for stitching, and a sure guide for a regular and uniform fold in all cases produced, which materially adds to the beauty and finish 20 of the manufactured article, also materially cheapens the cost of production.

What I claim as my invention, and desire to secure by Letters Patent, is—

1. In a creasing-machine, the combination, with the shafts D and E, of the grooved wheel 25 I, creasing-wheel J, slotted cloth-plate H, through which the grooved wheel I projects, the weighted lever O, and spring N, substantially as described.

2. In a creasing-machine, the combination, 30 with the shafts D and E, grooved wheel I, creasing-wheel J, slotted cloth-plate H, weighted lever O, and spring N, of the spring-presser L and adjustable guide K, substantially as described.

35 In witness whereof I have hereto set my hand this 6th day of November, 1879.

ROWLAND S. NORTON.
